UNITED STATES PATENT OFFICE.

FRANK KUHN AND JAY A. HAND, OF DETROIT, MICHIGAN, ASSIGNEES TO AMERICAN ELECTRICAL HEATER COMPANY, OF DETROIT, MICHIGAN, A CORPORATION OF MICHIGAN.

ELECTRICAL HEATING UNIT.

1,282,242.

Specification of Letters Patent.

Patented Oct. 22, 1918.

Application filed February 21, 1918. Serial No. 218,403.

To all whom it may concern:

Be it known that we, FRANK KUHN and JAY A. HAND, both citizens of the United States of America, and both residing at Detroit, in the county of Wayne and State of Michigan, have invented certain new and useful Improvements in Electrical Heating Units, of which the following is a specification, reference being had therein to the accompanying drawings.

The invention relates to electrical heating units of the exposed resistor type and has for its object simplicity in construction, thorough protection or guarding of the resistor, mechanical strength and ease in assembly. The invention consists in the novel construction as hereinafter set forth.

In the drawings:

Figure 1 is a perspective view of the unit; Fig. 2 is a sectional plan view of a portion of the unit;

Fig. 3 is a cross-section on line 3—3 of Fig. 2;

Fig. 4 is a cross-section on line 4—4 of Fig. 2;

Fig. 5 is a perspective view showing the manner of assembling the elements of the unit.

A are insulator strips, preferably formed of mica and which are centrally apertured at intervals with metallic eyelets B. C and C' are metallic strips of U-shaped cross-section, which embrace the opposite edges of the strip A and constitute a reinforcement therefor. These metallic strips are notched at D for engagement with brace bars E having coöperating notches F therein. The construction is such that by arranging a series of the strips A in parallel relation they may be spaced and held in this relation by engagement with the cross strips E. The resistor G, preferably in the form of a coil, is threaded through the eyelets back and forth between the strips so as to be distributed as uniformly as possible over the area of the unit. The threading may be performed before the cross-bars E on one side of the unit are placed in position, but when completed said cross-bars E will constitute a grid protecting the resistor from injury or short circuiting.

The unit is preferably inclosed in an outer peripheral band H formed of a sheet-metal strip, and the ends of the strips C and E may be engaged with notches in this band

and clenched, as indicated at I. At one point the band H is cut away at J for the passage therethrough of the terminal conductors. These conductors, K, are preferably mounted on an insulator block L, which in turn is mounted on a metal bracket member M having a segmental portion M' fitting against the band H. The inner ends of the terminal conductors K pass through apertures M² in the portion M' and are held from contact therewith by an insulator strip N, preferably of mica, which may be clamped between the member M' and the band H. Thus the terminals will be mechanically fixed in relation to the unit and electrically insulated from the frame thereof. The resistor is suitably connected to the portions of the terminals K projecting inward through the apertures M² by means of clamping screws K' which are readily accessible through the openings between the bars of the grid.

With the construction described the internotched and crossing metallic strips will form a strong mechanical structure without shielding to any great extent the radiation from the resistor, the mica strips will form thorough electrical insulation and the metallic eyelets therein will protect the edges around the apertures for the resistor both mechanically and from overheating. The unit is therefore as strong and substantially well protected as an armored resistor, and on account of the exposure of the resistor is more efficient as a radiant element.

What we claim as our invention is:

1. An electrical heating unit, comprising a peripheral band, a series of strips extending across the area inclosed by said band, each comprising a mica strip having a series of eyelets therein and binding strips embracing the opposite edges of said mica strips and notched at intervals, a resistor threaded through said eyelets back and forth between said strips, and cross-strips having coöperating notches therein for engagement with the notched edge of said binding strips and having their opposite ends extend through said band and clenched thereover.

2. An electrical heating unit, comprising a peripheral band having a portion cut away, a series of mica strips extending across the area inclosed by said band, a resistor threaded through said strips back and forth therebetween, terminal conductors con-

nected to said resistor and passing through the cut-away portion of said band, a member having a portion fitting against the periphery and secured thereto and having 5 apertures therethrough for the passage of said terminal conductors, and an insulator strip between said band and member, said

insulator strip maintaining said terminal conductors out of contact with said band and member.

10

In testimony whereof we affix our signatures.

FRANK KUHN.
JAY A. HAND.
